DESIGN FOR A DENTAL PROFILE RECORDER

William L. Schmitz, Jr., San Marino, Calif.

Application November 6, 1940, Serial No. 96,355

Term of patent 7 years

To all whom it may concern:

Be it known that I, William L. Schmitz, Jr., a citizen of the United States, residing at San Marino, in the county of Los Angeles and State of California, have invented a new, original, and ornamental Design for a Dental Profile Recorder, of which the following is a specification, reference being had to the accompanying drawing, forming part thereof.

Figure 1 is a view in side elevation of the dental profile recorder embodying my new design; Fig. 2 is a top plan view of the same; Fig. 3 is a view in end elevation of the same taken in the direction of the arrow 3 upon Fig. 1; and Fig. 4 is a view in end elevation taken in the direction of the arrow 4 upon Fig. 1.

I claim:

The ornamental design for a dental profile recorder, as shown.
